GAS FILLING APPARATUS
Hugh V. Holland, 103 Meadow Lane,
Oklahoma City, Okla.
Filed Jan. 12, 1961, Ser. No. 32,326
3 Claims. (Cl. 222—509)

This invention relates to an apparatus for controlling a fluid flow and more particularly to an apparatus suitable for filling balloons and other inflatable articles such as rubber boats and the like with a gas after which the gas filling tube of said article is ejected from said apparatus.

Various attempts have been made heretofore to design a suitable apparatus for filling such articles. These prior art devices have consisted of a nozzle for insertion into the filling tube of the inflatable article and a valve for controlling the flow of gas. When such an apparatus is used the filling tube of the article being filled must be removed by hand. This, of course, is time consuming.

It is, therefore, a principal object of the present invention to provide a gas filling device that obviates the disadvantages of the prior art devices.

It is another object of my invention to provide a gas filling apparatus whereby the filling spout of the item being filled with gas can be easily ejected after filling without touching the same with the hands.

It is another object of this invention to provide a gas filling apparatus whereby the flow of gas can be easily and accurately regulated.

These and other objects and advantages of the invention will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed wherein like numerals are employed to designate like parts throughout.

In said annexed drawings:

FIGURE 1 is an elevational view, partly in section, showing a preferred embodiment of my invention;

FIGURE 2 is a view from the top of the device of FIGURE 1;

FIGURE 3 is a cross-sectional view taken along the lines 3—3 looking in the direction of the arrows; and

FIGURE 4 is a front elevation of the device of FIGURE 1.

Referring to the drawings and to FIGURE 1 in particular the housing 6 is provided with a passageway 30 which is attached to the fluid supply 15 by means of the connection 14 which is preferably a screwed-in connection. Valve stem 18 is mounted within the passageway 30 and is urged upwardly by the resilient means so that the valve element 28 is in contact with valve seat 29 thus closing the passageway. The valve stem is moved downwardly by moving lever 20 toward rigid arm 7 thus opening the passageway. Resilient means 19 and 25 urge lever 20 to the normal position wherein the valve stem is seated thus closing the passageway.

Although it is believed that the operation of the device will be apparent from the foregoing description particularly when considered with the accompanying drawings, the following operating procedure will be given for even greater clarity. The filling tube of the balloon or the other item to be inflated is securely placed on

2

nozzle 13. The desired amount of gas is then allowed to flow into the item to be inflated by opening the valve regulated by lever 20. After the item has been inflated lever 20 is allowed to move to its normal position, lever 8 is pressed downward toward rigid arm 7 which disengages catch 32 from notch 33. The pistons 21 move forward the distance denoted by 24 due to the tension of resilient means 11 carrying disc 12 forward also which is sufficient to force the filling tube off nozzle 13.

While the foregoing description of the operation of the gas filling device is particularly applicable to inflating balloons and similar objects, the filling device has many other uses as will be apparent to those skilled in the art. As one example of such an additional use, it may be employed in charging the liquid contents of a container with a gas under pressure. A typical example of the latter is one in which cream is packed in a container under pressure of nitrous oxide gas so that, when the pressure is released, the nitrous oxide will expand, causing the cream to fluff or expand into a product resembling whipped cream. A suitable container for this product (cream) is a tin can although many other materials may be used in the actual construction of the receptacle. The container, of course, must be liquid and gas tight. The tin can or other suitable receptacle preferably is fitted with a self-sealing plug (such as rubber) in one end thereof through which the nozzle 13 is inserted to charge the container with gas. After the desired amount of gas has been injected into the container the nozzle is withdrawn.

The latching means is reset by pushing the disc toward the housing 6 until latch 32 engages notch 33. Tension means 16 holds the latching means in engagement until a positive force is applied to lever 8.

Numeral 34 designates an adapter or coupling provided with closing means and a passageway which leads to the main passageway 30. As will be apparent to those skilled in the art, the purpose of this adapter or coupling is to provide means whereby the fluid supply container 15 may be recharged when necessary. If desired, a pressure gauge 35 may be installed on the opposite side of the housing 6 to that side to which 34 is fitted as illustrated. It is to be understood that the use of the gauge is optional. When such a gauge is used it is necessary to provide a passageway in the housing leading from the gauge to the main passageway 30.

An alternative by less preferred method of mounting the pushing member 12 is by means of a single sleeve 21 which fits over and is in slidable engagement with the nozzle 13 rather than employing a pair of pistons. In this method a hole is drilled in the housing of the passageway 30. A portion of this hole is then reamed out to a diameter larger than the nozzle to a point short of reaching the passageway 30. This portion reamed out should be large enough to permit sleeve 21 to move freely therein. After this is accomplished the nozzle is inserted securely in the housing then the resilient member 11, sleeve 21 and pushing member 12 inserted in that order over the nozzle 13. Generally pushing member 12 is securely attached to sleeve 21. As in the preferred embodiment of the invention the pushing member 12 is held in proximity to the housing by means of the latching means 32 and 33.

While particular embodiments of the invention have been described, it will be understood, of course, that the invention is not limited thereto since many modifications may be made, and it is, therefore, contemplated to cover by the appended claims any such modifications as fall within the true spirit and scope of the invention. Thus, for example, the resilient means may consist of a metallic spring under tension or it may consist of elastic

means such as that provided by rubber or similar elastomer. Under some conditions a bellows arrangement may be used to provide the necessary resilience.

The invention having thus been described, what is claimed and desired to be secured by Letters Patent is:

1. A fluid filling device, the combination comprising: a housing having a passageway for connection to a fluid supply, valve means located in said passageway, said valve means including a valve seat and a valve stem, said valve stem being movably mounted in said valve means and cooperable with said valve seat to prevent fluid flow through said passageway and valve means at times while at other times permitting fluid flow therethrough, means for moving said valve stem, a nozzle projecting from said housing having a passageway in communication with the passageway in the housing, a pushing member slidably mounted on said nozzle characterized in that the plane of said pushing member is at a right angle to the longitudinal axis of said nozzle, resilient means urging said pushing member away from said housing, latching means for holding said pushing member in proximity to said housing thereby compressing said resilient means, the arrangement and construction of said valve means and pushing member being such that either may be actuated independently of the other, and means for disengaging said latching means.

2. A fluid filling device, the combination comprising: a housing having a passageway for connection to a fluid supply, valve means located in said passageway, said valve means including a valve seat and a valve stem, said valve stem being movably mounted in said valve means and

5

cooperable with said valve seat preventing fluid flow through said passageway and valve means at times while at other times permitting fluid flow therethrough, resilient means urging said valve stem to a position wherein fluid is prevented from flowing through said passageway and valve means, means for moving said valve stem, a nozzle projecting from said housing having a passageway in communication with the passageway in the housing, a pushing member slidably mounted on said nozzle characterized in that the plane of said pushing member is at a right angle to the longitudinal axis of said nozzle, resilient means urging said pushing member away from said housing, latching means for holding said pushing member in proximity to said housing thereby compressing said resilient means, the arrangement and construction of said valve means and pushing member being such that either may be actuated independently of the other, and means for disengaging said latching means.

3. The device of claim 2 where said resilient means urging said pushing member away from said housing is a bellows.
